GEORGE R. NEBINGER, OF LEWISBERRY, PENNSYLVANIA, ASSIGNOR TO
HIMSELF AND WILLIAM A. MIDDLETON.

Letters Patent No. 74,713, dated February 18, 1868.

IMPROVED CLOTHES-LINE CLAMP.

The Schedule referred to in these Letters Patent and making part of the same.

TO ALL WHOM IT MAY CONCERN:

Be it known that I, GEORGE R. NEBINGER, of Lewisberry, in the county of York, and in the State of Pennsylvania, have invented certain new and useful Improvements in Clothes-Line Ties; and do hereby declare that the following is a full, clear, and exact description thereof, reference being had to the accompanying drawings, and the letters of reference marked thereon.

In the annexed drawings, making a part of this specification, A represents an ordinary post or pillar, and B represents a block of wood or casting of metal, provided with flanges, and the inner side of said flanges each provided with a groove, *z*, to receive and for the trunnions *e e* of the block C to work in. The block C is made to fit between the flanges of the block B, and its trunnions to fit and work in the grooves thereof, and long enough to come out flush with the face of the block B, or whatever length required. The trunnions *e e* are then inserted into the grooves *z* of the flanges to the block B, and then said block B is screwed or secured in any suitable manner to the post A.

It will now be readily seen that, by securing one end of a rope or clothes-line, and then passing the other end through the opening between the flanges of the block B, and beneath the block C, and straining it up tight, then, by pressing with the thumb or finger on the back or outer side of the block C, so that it will catch, the cord or clothes-line D will be caught between the side of the post A and the end of the block C, and there securely fastened.

Whenever it may be required to unfasten or take the clothes-line down, all that is required is to pull on the outer end of the cord D, and thereby loosen the block C, which may then be raised by hand, and the cord or line D will slip out of the fastening.

Having thus fully described my invention, what I claim as new, and desire to secure by Letters Patent, is—
The block B, having a horizontal groove in its centre, whereby two flanges are formed, which have each a vertical slot, *z*, on their inner sides, when used in combination with the wedge-shaped block C, provided with trunnions *e e*, which work in said slots, as and for the purposes specified.

In testimony that I claim the foregoing, I have hereunto set my hand, this 17th day of December, 1867.

G. R. NEBINGER.
